INVENTOR

Ernest Leslie Ransome.

UNITED STATES PATENT OFFICE.

ERNEST LESLIE RANSOME, OF NEW YORK, N. Y.

CONCRETE CONSTRUCTION.

SPECIFICATION forming part of Letters Patent No. 694,580, dated March 4, 1902.

Application filed August 17, 1901. Serial No. 72,440. (No model.)

To all whom it may concern:

Be it known that I, ERNEST LESLIE RANSOME, a citizen of the United States, residing at New York, in the State of New York, have 5 invented an Improvement in Concrete Construction, of which the following is a full, clear, and exact description.

My invention relates to the construction of buildings of reinforced concrete; and it consists in the extension of a reinforced concrete floor over the external piers or walls of a building and in the formation of this extension into an exterior belt course, and when the floor rests upon external piers it further consists in integrally combining with the floor beam-like extensions above and below to carry the floor from pier to pier and at the same time to form the window-heads or curtain-walls terminating in window-heads for the 20 story below and the window-sills or curtain-walls terminating in window-sills for the story above.

The accompanying drawing illustrates my invention, in which—

25 Figure 1 is a front exterior view of the floor with its extensions. Fig. 2 is a cross-section of the same on line X X, and Fig. 3 is a cross-section of floor resting on a wall.

I carry out my invention as follows: After 30 the wall or piers have been brought to the required height the molds for the floor are set in place, and the floor is extended over the wall or piers and molded into a belt course A', as in Figs. 2 and 3. When the floor A has to rest upon piers, it is made with the 35 downward extension B, which extends to the windows C, of which it forms the head, and rests upon the piers D, which it caps, as at B'. Between the piers it can be reduced to 40 any required thickness, as at B'', Fig. 2. This extension is reinforced with the tension-bar E, which by preference extends the length of the building. To the floor A, by preference after it has hardened and the piers G 45 have been built, is also added the upper extension F, placed between the piers G. This extension is made of one integral piece with the floor by means of the coil-joint H or other suitable union, and it extends upward to the 50 window K, of which it is the sill. It is by

preference rabbeted into the piers. The advantages of this floor are, first, it thoroughly binds the building together, extending as it does entirely across the walls and piers; second, it affords an architectural feature at a 55 trivial cost; third, by the downward extension a deep beam is formed for supporting the floor-load, while it also fulfills all the functions of a window-head and curtain-wall; fourth, by the upward extension the depth of the beam is 60 further increased and extended from Y to Y, Fig. 2, and thus its tensional and compressive stresses are greatly lessened.

By the term "belt course" I include any other distinctive feature into which the exterior thickness of the floor could be molded.

Having thus fully described my invention, what I claim, and desire to secure by Letters Patent, is—

1. A reinforced concrete floor, extending 70 to the exterior face of a building, and there forming a belt course, substantially as described.

2. A reinforced concrete floor extending 75 to the exterior face of a building, and capping the piers thereof, substantially as described.

3. A reinforced concrete floor extending to the exterior face of a building, capping the piers thereof, and forming a belt course, sub- 80 stantially as described.

4. A reinforced concrete floor extending to the exterior face of a building, and having a downward extension which forms a head or lintel to the windows below, substantially as 85 described.

5. A reinforced concrete floor extending to the exterior face of a building and there forming a belt course with a downward extension forming heads or lintels to the windows below, substantially as 90 described.

6. A reinforced concrete floor extending to the exterior face of a building and there forming a belt course, capping the piers and windows below, substantially as described. 95

7. A reinforced concrete floor extending to the exterior face of a building with an upward window-sill extension, substantially as described.

8. A reinforced concrete floor extending 100

to the face of a building and there forming a belt course with an upward window-sill extension, substantially as described.

9. A reinforced concrete floor extending 5 to the face of a building with downward and upward extensions, substantially as described.

10. A reinforced concrete floor extending

to the face of a building and there forming a belt course and with downward and upward 10 extensions, substantially as described.

ERNEST LESLIE RANSOME.
